UNITED STATES PATENT OFFICE

CARLO COHEN-VENEZIAN, OF TURIN, ITALY

CRANE

Application filed March 5, 1931, Serial No. 520,453, and in Italy March 13, 1930.

This invention relates to cranes and similar lifting devices, particularly of the kind adapted for location on vehicles and the like, and has for its object a crane construction by means of which a crane is provided which has a small weight, large lifting power, useful radius and height of jib when in operative conditions, said crane being able of quick and easy operation and requiring a small space when in inoperative conditions, say when the vehicle carrying it is running.

The present invention also comprises means for arrangement of a crane on a vehicle having spring suspension means and resilient tires on its wheels, and includes particular provisions for cranes mounted on vehicles of such class.

On the annexed drawings an embodiment of this invention is shown by way of example.

In said drawings

Figure 1 is a side view of a vehicle having a crane according to this invention;

Figure 2 is a front view of the vehicle shown in Fig. 1;

Figure 3 is a side view of the vehicle in running conditions;

Figure 4 is a fragmentary side view on an enlarged scale of the crane with parts omitted;

Figure 5 is a plan view of Fig. 4;

Figure 6 is a section on line 6—6 of Fig. 5 as seen from a direction opposite the direction of arrows;

Figure 7 is a section similar to Fig. 6 as seen in the arrows direction.

In the embodiment shown in Figures 1-3, 1 denotes the frame of a vehicle supported by wheels 2, said vehicle being of any preferred construction as a motor driven or trailed one; on platform 3 of said vehicle, in a position adjacent to one of the vehicle axles, a crane hereinafter described is mounted for rotation around a vertical axis, to be carried in any desired operative position with the end of its jib lying beyond the space occupied by the vehicle.

In the frame portion where the crane is located, legs 4 are hinged under platform 3, each of said legs having a screw-threaded extension 5 on its end; said extensions 5 thus

provide abutments adapted to be forced against ground to secure a firm support for the vehicle platform. Said legs 4—5 when in operative conditions shown in Figures 1 and 2 provide a firm and stiff support for platform 3 and thus they prevent said platform from oscillating or taking up an inclination under the load carried by said crane as it could happen should the load be supported by resilient suspension means as spring axles 6 and resilient tires of platform 3. On the other hand said legs 4—5 do not restrict the normal vehicle running because owing to their hinge connection with platform 3, they may be lifted into inoperative position as shown in Figure 3.

The crane comprises a vertical sleeve 6 journaled over a vertical pivot stud 7 fastened on vehicle platform 3, and said sleeve 6 is secured intermediate two plates 8, 8' 70 spaced from and connected with each other by transverse members 39, 40, said plates providing the crane body.

On the outer faces of said plates 8, 8' are fulcrumed at 9 the ends of chords 10, 10' of 75 a truss girder forming the crane jib and having a pulley 11 loose on its free end.

The crane winch comprises a drum 12 mounted for rotation intermediate plates 8, 8' and adapted to receive or pay a rope 13 80 which runs over pulley 11. Said drum 12 is driven by means of gears 14, 15, 16 and 17 and of a crank 18 which is adapted to be fastened on either end of the shaft 41 carrying pinion 17 and extending beyond plates 8, 8'. 85 Intermediate such plates 8, 8' is also mounted to move by means of rollers 19, an arm 20 which carries a counterweight 21 intended to balance the crane load. The arm 20 has on each side of its web a rack 22 meshing with a pinion 23; said pinions 23 are solid with spindles 24 mounted for rotation in cross members 39 interconnecting plates 8, 8'. Each spindle 24 has a bevel pinion 25 fastened thereon, and said pinions 25 are in 90 mesh with bevel pinions 26 solid with a transverse spindle 27 which extends at each end beyond plates 8, 8' and may be driven by a removable crank (not shown) on either side of the crane. A ratchet pinion 28 is 100

solid with spindle 27, said ratchet pinion cooperating with a pawl 29 to prevent the gear from running back.

Counterweight 21 has an eye 30 for attaching a rope 31 which connects said counterweight 21 with the end of jib 10, 10' and a loose roller or pulley 32 is journaled in two uprights 33, 33' fastened on plates 8, 8', said pulley 32 being intended to receive and support rope 31 when jib 10, 10' is in its depressed position.

Owing to interconnection provided by rope 31 the positions of jib 10-10' and of counterweight 21 are at any time in relation with each other.

For operation spindle 27 is actuated by means of a crank, not shown, engaged on the end of said spindle and thus the gear 26, 25, 24, 23, 22 with counterweight 21 is moved longitudinally in either direction, the described device lifting jib 10 as shown in Figure 2 or leaving it to take its depressed position of Figure 3. The sleeve 6 journaled over the pivot stud 7 of the vehicle platform, 25 has a flange 37 solid with it, said flange being provided with recesses at its periphery.

The crane is moved by hand around the stud 7 and it is locked in angular position around said stud as required for the operation 20 to be carried out, by means of a bar 34 fulcrumed in plates 8, 8' and having a projection 35 adapted to engage recesses 36 of said flange 37. Actuating arms 38 extend from bar 34 for its actuation to release or engage 25 projection 35 from or in recesses 36.

When the vehicle is in running conditions the crane is in the position of Figure 3, with the crane jib 10-10' depressed and counterweight 21 in its position adjacent to crane 40 body 8, 8' and said crane is positioned in register with the longitudinal middle portion of the platform 3 leaving the most of the same free for carrying a load.

When the crane is to be used, legs 4 are lowered and their end sleeve 5 are forced against ground to afford a firm support to platform 3 and then spindle 27 is actuated as above described to move counterweight 21 away from the axis of stud 6; the rope 31 is thus tensioned and it lifts the jib 10, 10'. Thereafter parts 38 and 34 are actuated to release projection 35 from recesses 36 of stationary plate 37, the crane jib is moved by hand around stud 6 to carry it to the 55 required angular position and thereafter it is locked again in any desired position by means of parts 38, 34, 35.

Figures 1 and 2 show the crane in the position it must be carried to lift a load located 60 on a side of the vehicle 3, but of course jib 10, 10' may also be caused to project on the vehicle front.

To lift the load a crank 18 is actuated to drive drum 12 and wind up the lifting rope 65 13 on said drum.

After done with, the crane is carried back in its position along the vehicle axis and spindle 27 is actuated to move counterweight 21 towards crane body 8, 8' the jib 10, 10' being thus depressed.

The described construction provides a crane having small transverse size which takes up a very small space; further the described crane may be easily and quickly carried from operative into inoperative position and vice versa and when carried in inoperative position, the crane has its jib in depressed position with counterweight located within the vehicle outline as required for travelling.

What I claim as my invention and desire to secure by United States Letters Patent is:

1. A vehicle crane comprising a body consisting of two plates spaced from and connected with each other, means in said body for pivotal mounting on the vehicle, a jib fulcrumed on said body plates, a lifting winch located in said body, an arm mounted to move longitudinally intermediate said body plates, a counterweight on the outer end of said arm, a gear located intermediate said body plates to move said arm and a member connecting said outer end of said arm with the free end of said jib to raise and depress the same in accordance with outward and inward movements of said arm and counterweight with respect to said crane body.

2. A vehicle crane comprising a body consisting of two plates spaced from and connected with each other, means in said body for pivotal mounting on the vehicle, a jib fulcrumed on said body plates, a lifting winch located in said body, an arm mounted to move longitudinally intermediate said body plates, a counterweight on the outer end of said arm, a gear located intermediate said body plates to move said arm, said gear comprising racks on opposite sides of said arm, pinions fulcrumed in said crane body and meshing with said racks and means for driving said pinions in opposite directions, and a member connecting said outer end of said arm with the free end of said jib to raise and depress the same in accordance with outward and inward movements of said arm and counterweight with respect to said crane body.

3. A vehicle crane comprising a body consisting of two vertical plates spaced from and connected with each other, means in said body for pivotal mounting on the vehicle frame, a jib fulcrumed on said vertical plates, a lifting winch located intermediate said plates, and arm mounted to move longitudinally intermediate said plates and extending beyond them, a counterweight on the outer end of said arm, means to move said arm and a flexible tie connecting said outer end of said arm with the free end of said jib.

4. A vehicle crane comprising a vehicle frame having axles, a vertical pivot stud on

said vehicle frame in register with the middle of one of said axles, a crane body consisting of two vertical plates spaced from and connected with each other, a sleeve in said body for pivotal mounting of the same on said stud, a jib fulcrumed on said plates, a lifting winch located intermediate said plates, an arm mounted to move longitudinally intermediate said plates and extending beyond them, a counterweight on the outer end of said arm, means to move said arm and a flexible tie connecting said outer end of said arm with the free end of said jib.

5. A vehicle crane comprising a body consisting of two vertical plates spaced from and connected with each other, means in said body for pivotal mounting on the vehicle frame, a jib fulcrumed in said vertical body, a lifting winch located intermediate said plates, an arm mounted to move longitudinally intermediate said plates and extending beyond them, a counterweight on the outer end of said arm, means to move said arm, a flexible tie connecting said outer end of said arm with the free end of said jib, and means on said crane body cooperating with said flexible tie to provide a support for engagement by the same at an intermediate point thereof before the jib becomes in its lowermost position.
